UNITED STATES PATENT OFFICE.

ELEAZER KEMPSHALL, OF NEW BRITAIN, ASSIGNOR TO THE KEMPSHALL PATENT BUTTON FASTENER COMPANY, OF DERBY, CONNECTICUT.

BUTTON-SETTING INSTRUMENT.

SPECIFICATION forming part of Letters Patent No. 310,525, dated January 6, 1885.

Application filed June 27, 1884. (No model.)

To all whom it may concern:

Be it known that I, ELEAZER KEMPSHALL, a citizen of the United States, residing at New Britain, in the county of Hartford and State 5 of Connecticut, have invented certain new and useful Improvements in Button-Setting Instruments, of which the following is a specification.

My invention relates to an improvement 10 upon the button-setting instrument patented to me May 20, 1884, No. 298,984.

In the accompanying drawings, Figure 1 is a side elevation of my improved button-setting instrument. Fig. 2 is a transverse section 15 of parts thereof on line $x-x$ of Fig. 1. Fig. 3 is a transverse section of parts thereof, together with a plan view of the lower jaw. Fig. 4 is a longitudinal section of said lower jaw on line $y-y$ of Fig. 3, and Fig. 5 is a side 20 elevation of the lower jaw, with the side gage represented as broken away and removed in order to better show the other parts.

The four last figures are on an enlarged scale.

The upper jaw or member, A, may be of any 25 ordinary character.

The changes which I make in my present improvement are found upon the lower jaw, B. I still retain the yielding guide-block a , slotted longitudinally, the anvil b , and the 30 holding-spring c within the slot of said guide-block. Instead of slotting the guide-block through from side to side, I leave a solid wall or connection upon one side, as shown at d , which wall answers as a stop or gage against 35 which one end of the head bar or base of the fastener may rest in locating its position in the instrument.

The broken lines in Fig. 2 indicate one of my fasteners as properly located within the 40 setting-instrument.

Instead of supporting the anvil b within the jaw B upon both sides of the yielding block, I support it only upon one side, and I prefer to form it in the form of an angle-iron with 45 one wing secured to the side of jaw B, while the other, which forms the anvil proper, terminates within said slot, as shown most clearly in Figs. 2, 3, and 5.

For cheaply securing the holding-spring c 50 in place, I slot the yielding guide-block through from end to end, as shown, and then remove

a portion of the metal at each end upon one side of said slot, so that the spring may be secured after insertion by bending its ends over the ends of the block upon that side, as shown 55 in Fig. 4.

C designates a spring, which rests upon the end at the longer side of the guide-block, as shown in Fig. 4, for holding the guide-block in the position represented when not displaced by other force. Upon one side of this spring C, I form a wing or guide, f , which extends up by one end of the anvil, so as to support one end of the head bar or base of my fastener when it is seated in place, as shown 60 in Fig. 2. By reference to said figure it will be seen that the fastener is securely held in its place within the guide-block by means of the spring C and opposing wall of the guide-block acting upon the two flat sides of the fastener, 65 and by the solid wall d of the yielding block a and the guide f on the yielding spring C, acting, respectively, against the two ends of the base or head. All of these guides except 70 the anvil yield, so as to be out of way of the central prong or hook of the fastener as the 75 operation of bending it progresses.

The spring C, with the wing or guide f , may be used in connection with the instrument shown and described in the patent hereinbefore named, and without any of the other improvements herein described, and when so used will be considered as of my invention.

I am aware that a prior patent shows an instrument for setting buttons by means of a sample form of fastener, which instrument has two movable pistons constructed to work in guide-ways formed in the lower jaw, the ends of which pistons act under the influence of a lever upon the ends of the wire staple to press 85 them toward the upper jaw. Such an instrument is hereby disclaimed. The pistons in said instrument do not yield away from the companion jaw as the jaws are brought together, and consequently they are not yielding 90 guides in the sense of that term as used by me.

I claim as my invention—

1. In a button-setting instrument, the combination of the slotted guide-block having the 95 solid wall d extending along one side of the slot thereof, and the anvil b , secured to the jaw

B, and terminating within the slot, substantially as described.

2. In a button-setting instrument, the combination of the yielding guide-block, slotted longitudinally from end to end, the anvil *b*, projecting into said slot, and the spring *c*, extending longitudinally through the slot by the side of the anvil, and with its ends bent to one side, substantially as described.

10 3. In a button-setting instrument, the combination of an anvil, a yielding guide-block slotted longitudinally, and the spring *C*, for pressing upon the end of the guide-block, and

having the wing or guide *f* extending upward by one of the ends of the anvil, substantially 15 as described.

4. In a button-setting instrument, the combination of the anvil, the yielding guide-block for supporting the sides of the fastener, and yielding guides for supporting the two ends of 20 the base of the fastener, substantially as described.

ELEAZER KEMPSHALL.
